[57] **CLAIM**

The ornamental design for a weight bearing shower curtain rod, as shown and described.

DESCRIPTION

FIG. 1 is a front and top perspective view of a weight bearing shower curtain rod embodying the invention;

FIG. 2 is an enlarged top view of FIG. 1;

FIG. 3 is a left end view of FIG. 1;

FIG. 4 is a front view of FIG. 1;

FIG. 5 is a back view of FIG. 1;

FIG. 6 is a right end view of FIG. 5 ; and,

FIG. 7 is a bottom view of FIG. 5 .

The broken line showing of a partial curtain and structure is for illustrative purposes only and forms no part of the claimed design.

The claimed design is shown broken away in FIGS. 2-7 for ease of illustration.
